US00D928593S

(12) **United States Design Patent** (10) **Patent No.:** **US D928,593 S**
(45) **Date of Patent:** **** Aug. 24, 2021**

(54) **WIRE MANAGER**

(71) Applicant: **Seasonal Specialties, LLC**, Eden Prairie, MN (US)

(72) Inventor: **Steven J. Altamura**, Scarsdale, NY (US)

(73) Assignee: **Seasonal Specialties, LLC**, Eden Prairie, MN (US)

(**) Term: **15 Years**

(21) Appl. No.: **29/680,826**

(22) Filed: **Feb. 20, 2019**

Related U.S. Application Data

(62) Division of application No. 29/594,082, filed on Feb. 15, 2017, now Pat. No. Des. 847,611.

(57) **CLAIM**

The ornamental design for a wire manager, as shown and described.

DESCRIPTION

FIG. 1 is an environmental perspective view of a wire manager.

FIG. 2 is a perspective view of thereof.

FIG. 3 is a top plan view of thereof.

FIG. 4 is a bottom plan view of thereof.

FIG. 5 is a right side view of thereof.

FIG. 6 is a left side view of thereof.

FIG. 7 is a front view of thereof; and,

FIG. 8 is a back view of thereof.

The broken line showing of the pole and electrical cord in FIG. 1 illustrates the environment of the claimed design and forms no part thereof. The remaining broken lines in the drawings illustrate portions of the wire manager and form no part of the claimed design.

1 Claim, 3 Drawing Sheets
